UNITED STATES PATENT OFFICE

CHARLES F. KURTZ, OF ROCK ISLAND, ILLINOIS, ASSIGNOR OF ONE-HALF TO H. E. LONG,
OF ROCK ISLAND, ILLINOIS

COIN-OPERATED VENDING MACHINE

Original application filed November 11, 1927, Serial No. 232,522. Divided and this application filed February 25, 1929. Serial No. 342,366.

This invention relates to coin operated vending machines, and the subject matter of this specification has been divided out of my pending application for patent on coin operated vending machines, filed November 11, 1927, under Serial No. 232,522.

The present invention has particular reference to coin operated vending machines of the type in which a series of packages is supported on an inclined plane in such manner as to feed automatically towards a discharge opening, and, in some cases, the column of packages will bear against the lowermost package with sufficient force to interfere with the operation of the mechanism which assists in the release and discharge of such package. One of the objects of the present invention is to provide novel electrically operated package releasing apparatus which will not be affected by the pressure of the packages in the inclined slide, and which will operate efficiently in the discharge of successive packages from the machine.

Another difficulty in machines of the type mentioned which are electrically controlled arises from a tendency of the mechanism to act too rapidly after being set in motion, so that there is danger of the parts returning to normal position before the desired functions have been fully carried out and the actuating coin freed from the chute in which it is temporarily held. Another object of the invention is to retard the action of the various mechanisms and prolong the cycle of operations to such an extent that all of the parts will have time to fully operate. This is accomplished in part by two electric magnetic systems, one of which is actuated by a coin whereby the second is energized and the force thereof employed for operating the package releasing mechanism and resetting the various mechanisms. Another object of the invention is to provide electrically operated mechanism for the release of the lowermost of the series of packages and cause a positive discharge thereof, which will act as a bar to the next succeeding package in the column.

Other objects and advantages will appear in the course of the specification, and with said objects and advantages in view, this in-

vention consists in the several novel features hereinafter fully set forth and claimed.

The invention is clearly illustrated in the drawings accompanying this specification in which—

Figure 1 is a plan of a coin operated vending machine embodying a simple form of the present invention with the cover plate and a certain partition removed to show parts that would otherwise be hidden from view;

Fig. 2 is a plan of the primary switch mechanism and the electromagnet controlled thereby, showing the switch closed;

Fig. 3 is a plan of the parts seen in Fig. 2 with the switch open;

Fig. 4 is a view partly in side elevation and partly in vertical longitudinal section, of the parts seen in Fig. 1, the line of section being indicated at 4—4 in Fig. 1;

Fig. 5 is a detail cross section taken on the line 5—5 of Fig. 3;

Fig. 6 is a fragmentary plan of certain actuating mechanism for the package releasing device and showing the parts in their normal or inactive position; and

Fig. 7 is a diagrammatic view of the electrical connections employed in the machine.

Referring to said drawings, the invention is illustrated in its simple or unitary form, but two or more units can be combined in a multiple form of the device, if desired, said units being enclosed within a casing of suitable size, and used for dispensing different kinds of confections, or for several packages of the same kind, or for dispensing other small articles of merchandise.

As illustrated in the drawings, the invention is contained within a casing comprising a pair of sides 1, ends 2 and 3, a floor 4, and a top 5, preferably composed of glass. The operative parts of the device are shown in Figs. 1 and 2 in an intermediate position occupied after a coin has been introduced and the operative parts of the mechanism moved to a position in which the lowermost package is being discharged. Supported in spaced relation with the top 5 is a partition 6 forming the bottom of a passage or chute 7 of suitable dimensions to contain a series of packages of the kind to be vended by the ma-

55

chine. A number of such packages are indicated at 8 and may consist of rolls of mints or other confections, packages of gum, or other small articles of manufacture.

5 The casing is designed to be supported in an inclined position, as indicated in Fig. 4, with a sufficient slope to cause a ready movement by the force of gravity of the packages towards a throat 9 at the lower end of the chute. Below the throat 9 is an angle plate 10 which forms the bottom of a pocket into which the lowermost package drops, when permitted to do so, and below the pocket is a discharge chute 11 leading to a discharge opening 12 in the end 3 of the casing.

10 Slidable on the upper part of the angle plate 10 is a plunger 13, to the ends of which are attached the ends of a frame 14, said frame ends being united by a bar passing beneath the bottom of the chute 11. The upper plate of the plunger 13 is slidable beneath an angle plate 15, one face of which forms one side of the throat 9. Spaced from the plunger is a guard frame 17 swingingly supported at 15 *a*, said frame forming the inner side of the pocket when the parts are in a normal position, but which is moved backward from the position seen in Fig. 4 during the remainder of the movement of the plunger in discharging a package from the throat. The ends of the guard frame are engaged by pins 19 carried by the ends of the frame 14, which pins hold said guard frame in its proper relation to the plunger and prevent surreptitious removal of the lowermost package. Normally the plunger occupies a position in advance of the one shown, whereby the lowermost package falls into the pocket between the plunger 13 and guard frame 17.

20 40 Mounted on the floor 4 is a supporting bracket 16, to the upper part of which is pivoted a plate 18, as at *b*, one corner of said plate being connected to the plunger actuating frame 14 by means of a link 20. In line 25 with said plate 18 is a coupling 22, and projecting from one end of said plate is a rod 23 connected by a link 24 with the opposite corner of the plate 18 as at *c*.

45 Secured on the floor 4 is a solenoid 25 containing a cylinder 25^a in which is a slidable bar plunger 26. On the outer end of said plunger is a collar 27 engaged by a fork on the end of a lever 28 fulcrumed as at *d* on a bearing bracket mounted on the floor. The 50 other end of the lever 28 is connected by a link 29 with a lever 30 fulcrumed at *e* and pivotally connected with the coupling 22, above referred to. Said levers 28 and 30, together with the associated parts, are held in 55 their normal position with the plunger 26 extended by means of a coiled spring 31.

55 The solenoid 25 being electrically energized, the plunger 26 is drawn inwardly (an intermediate position of which is illustrated in the drawings) thereby swinging the levers

28 and 30 in a direction to move the coupling 22 in the same direction as the plunger is moved. The movement of said coupling is imparted through the rod 23 and plate 18 to the plunger actuating frame 14, thereby moving said frame and therewith the plunger 13 downwardly and inwardly beyond the position shown in the drawings. The plunger forces ahead of it the lowermost package contained in the pocket and said package moves the guard frame 17 inwardly until the passage is cleared permitting the package to drop into the chute 11 from which it is discharged by its own momentum.

70 15 In the package discharging movement of the plunger 13, the upper plate thereof closes the throat 9 thereby forming a support and obstruction to the next succeeding package in the column. The plunger being returned to its normal position, this last mentioned package drops into the space between the plunger and guard frame ready to be discharged in its turn while another package is tipped into an inclined position in the throat. This latter package receives the bulk of the pressure exerted by the column of packages in the chute, and, consequently, the one which is in position to be discharged is not affected thereby. There is little or no interference with the plunger 13 in its movement for discharging 75 the package.

75 20 The end of the cylinder 25^a is preferably closed, the cushion of air therein operating to retard the movement of the plunger 26 and correspondingly prolong the duration of the movement of the coupling 22 and parts connected thereto. This will defer the operation of the mechanism for returning the various devices to a normal position and will give all of said devices ample time to operate, 80 as will be hereinafter more fully set forth.

85 25 In the upper end of the casing is a coin slot 32, in which a coin 32, of established size and value, may be inserted passing downwardly along a curved passage 34 into a chute 35, 90 at the lower end of which the coin comes in contact with one arm of an angle plate 36 pivotally supported as at *f*. The other arm of said angle plate is in engagement with a slide plate 37, carrying a pair of switch terminals 38 adapted for contact with stationary terminals 39 mounted on a frame 40. The contact of the coin with the angle plate causes a movement of the plate 37 from the position shown in Fig. 3 to that shown in Fig. 2, thereby closing the switch of the circuit through an electrical system in which is contained an electromagnet 41 in proximity to which is supported an armature 42, pivoted at *g* on a post fixed in the floor 4. Fixed to 95 the armature is a spring 45, on the end of which is a contact 46, normally out of contact with a terminal 47 electrically connected with the solenoid 25. The switch 38-39 being closed and the magnet 41 energized, the ar- 100

mature 42 is attracted thereto causing a contact of the points 46 and 47 and closing a circuit through the solenoid 25 which operates in the manner hereinbefore set forth.

The armature 42 being attracted toward the magnet 41, the end thereof slides past the nose of the catch 48, which engages such end and temporarily locks the armature in such position. The action of the catch is impelled by means of a spring 49, which is supported to bear against the catch 48 to hold it yieldingly in engaging position. The catch is provided with an extension 51 in the end of which is a set screw 52 bearing against a block 53 on one end of a slide bar 54 which is slidably mounted in brackets supported by the floor 4. Pivoted on the floor as at *h* is a bell crank lever 55, one of the ends of which is connected by a rod 56 with the coupling 22, and the other end with the slide bar 54. At the latter part of the inward movement of the plunger 26, the lever 55 is operated to cause the slide bar 54 to move in a direction to force the catch 48 outwardly (see Fig. 3), permitting the return of the armature 42 to an open position.

The movement of the slide bar 54 also causes a push plate 57 supported thereby to dislodge the coin from the lower part of the chute, forcing it sideways therefrom and into a discharge chute 58, from which it passes downwardly into a box 59, removably supported beneath the floor 4. The push plate 57 also blocks the passage of a second coin that might have been introduced into the coin slot, and prevents the same from functioning until the first coin is deposited in the box and the mechanism re-set for another operation. The slide bar 54 also carries an arm 60, the end of which engages a lug on the side plate 37, operating the same in a direction to release the switch points 38-39 coincidently with the release of the coin, and just preceding the release of the catch 48.

The coin chute contains a slot 62 of relatively less width than the diameter of the coin it is designed to use for operating the machine. For example, if the established coin is a five cent piece, and a one cent piece is inserted in the slot 33, it will pass through the slot 62 without affecting the machine. By tipping the machine into a vertical position, a coin of any size that will enter the coin slot will drop straight down against the angle plate 36 and operate the machine. To prevent such operation, a wire guard 63 is pivoted at one side of the coin chute, and provided at its outer end with a weight 64. When the casing is supported in a vertical position, said weight will swing the guard into position with the bent end thereof projected into the passageway of the coins, so as to intercept the movement of any coin entering the chute. As the casing is returned

to an inclined position the weight swings the guard upwardly permitting the coin to resume its course. If the intercepted coin is one of the regular ones for operating the machine it passes on down the chute into contact with the angle plate 36. If it is of smaller size it drops through the slot 62 as before mentioned.

To prevent accidental release of a package, such as might be caused by shaking the machine to such an extent as to operate some of the parts, a lock is provided for the plunger 26 consisting of a catch 65 pivoted at *i* and adapted for engagement with the outer flange of the collar 27 when the plunger is at its extreme outer position, as shown in Fig. 6. This engagement is made positive by means of a coiled spring 66 interposed between said catch and the side of the casing. Near said catch an L-shaped lever 67 is pivoted, as at *k*, said lever having an upwardly turned arm 68, which bears against the inner face of the catch 65. The short arm of said lever is connected by a rod 69 with a plate 70 fixed to the armature 42 so as to project beyond the pivotal point thereof. The initial movement of the armature is thus imparted through the rod 69 and lever 67 to the catch 65 to release the same from engagement with the plunger, and permit the same to function. The timing of the devices is such that the catch is released just preceding the contact of the terminals 46 and 47 by means of which circuit for the solenoid is closed. Upon the armature being disengaged from the magnet 41, the lever 67 is again moved to withdraw the arm 68 and permit the reengagement of the catch 65 with the plunger 26 when the latter is moved outwardly again.

The arrangement of the electrical system is substantially as laid out in Fig. 7, the wires A and B indicating main lines which are connected with a source of electrical energy, not shown in the drawing. From the wire B a wire C extends to the solenoid 25, from which another wire D leads to the terminal 47. From the wire C a wire E leads to the switch points 39 and the terminals 38 are connected by a wire F with the magnet 41. Another wire G leads from said magnet to the wire A and the contact 46 is also connected with the last named wire.

The cycle of operation is as follows: Upon a coin being inserted in the slot 33, it passes downwardly and strikes against the angle plate 36 closing the switch points 38-39, whereby the magnet 41 is energized and actuates the armature 42. This movement of the armature 42 releases the catch 65 and closes the contact points 46 and 47, thereby closing a circuit through the solenoid 25. This results in the operation of the package discharging devices through the action of the levers 28 and 30. The solenoid being energized, the plunger is drawn up

ward and near the end of the movement of the plunger, the slide bar 54 is moved far enough to discharge the coin from the coin chute, open the switch points 38-39 and release the catch 48 (see Fig. 3) permitting the return of the armature 42 to its original position, and thereby breaking the contact between the contact points 46 and 47 of the solenoid.

Upon the plunger 26 moving outwardly again, the rod 56 is again moved forwardly rocking the lever 55 and returning the slide bar 54 to an inoperative position (see Fig. 2). While the complete cycle of movements appears to be performed instantly, there is a brief interval between the several movements which gives a retarding effect thereto, and provides ample time for all of the parts to act in their desired sequence. This is aided by the retarded movement of the plunger 26 against the air cushion, above referred to. The inward movement of the plunger 26 from the position shown in Fig. 6 past that seen in Fig. 1 is imparted to the package discharging plunger 13 through its connections with the plunger 26, and the plunger 13 is thereby moved backwards and downwards thereby discharging the lowermost package from the pocket into the chute 11. Upon the outer or return movement of the plunger 26, the package discharging plunger 13 is returned to its normal position, thereby permitting another package to fall into the space between the plunger 13 and guard plate 17.

The inclined position in which the casing is held not only aids in the movement of the packages therein, but it also places such packages in a convenient position for display.

While the invention has been set forth herein for use in dispensing packages of a smaller type, it may be adapted for the automatic sale of larger packages, of a uniform shape and size, such as bread, breakfast foods, coffee, tea and many others. The size of the machine would have to be correspondingly increased. The machine is found to operate most satisfactorily when the parcel chute is inclined at an angle of approximately forty-five degrees with its support.

I claim:

1. A device of the class described comprising a solenoid including a plunger reciprocating therein, dispensing mechanism actuated by said plunger, connections between said plunger and said dispensing mechanism to impart the movements of the plunger to said dispensing mechanism, an electric system for said solenoid having normally open terminals, an electromagnet, the armature of which is arranged to close said terminals, an electric system for said electromagnet having a coin operated electric switch mechanism, and switch opening mechanism for

said electric switch operatively connected to the plunger of said solenoid.

2. A device of the class described comprising a solenoid including a plunger reciprocating therein, mechanism actuated by said plunger, connections between said plunger and said mechanism to impart the movements of the plunger to said mechanism, an electric system for said solenoid having normally open terminals, an electromagnet, the armature of which is arranged to close said terminals, an electric system for said electromagnet having a coin operated electric switch mechanism, a spring actuated catch arranged to engage said armature and hold the same in its attracted position, and a catch disengaging member actuated by said electric switch mechanism.

3. A device of the class described comprising a solenoid including a plunger reciprocating therein, mechanism actuated by said plunger, connections between said plunger and said mechanism to impart the movements of the plunger to said mechanism, an electric system for said solenoid having normally open terminals, an electromagnet, the armature of which is arranged to close said terminals, an electric system for said electromagnet having a coin operated electric switch mechanism, a latch engaging the plunger of said solenoid when in normal position, and latch disengaging means operatively connected to said armature.

4. A device of the class described comprising a solenoid mechanism for actuating dispensing mechanism and including a movable element and an electric system connected with said solenoid and having normally open terminals causing an open circuit in said system, an electromagnetic system with a normally open switch and an armature operatively connected with one of said terminals to close said terminals upon the initial movement thereof, coin controlled devices adapted to close said switch, a spring controlled catch for said armature, a movable member adapted for the release thereof, connections between the movable element of said solenoid mechanism and said releasing member to move said member and thereby release said catch at the end of the initial movement of said element, and connections between said movable member and said switch to open the same coincidently with the release of the catch.

5. A device of the class described comprising a solenoid mechanism for dispensing mechanism and including a movable element, an electric system connected therewith and having normally open terminals causing an open circuit in the system, an electromagnetic system with a normally open switch and an armature operatively connected with said terminals to close the same upon the initial movement of the armature, a coin

chute and coin controlled mechanism operatively connected with said switch to close the same, a movable bar and coin discharge supported thereon at the inner end of said 5 coin chute, an arm on said bar adapted to operate said switch to open the same, and means between said movable element of the solenoid mechanism and said bar to actuate the same near the end of the movement of 10 said element.

6. A device of the class described comprising a solenoid mechanism and movable element thereof for dispensing mechanism, an electric system connected with said solenoid 15 mechanism and provided with normally open terminals causing an open circuit in said system, an electromagnetic system with a normally open switch and armature capable of closing said terminals upon being operated, 20 a catch for said armature to hold the same in contact with the magnet, a coin chute and mechanism for receiving the impact of a coin and closing said switch, a movable bar operatively connected with the movable element 25 of the solenoid adapted for the release of said catch, a coin discharge supported by said movable bar, and a connection between said bar and said switch to open the same upon the bar being actuated coincidently 30 with the release of said catch and discharge of the coin.

7. In a device of the class described, including dispensing mechanism, a solenoid apparatus for operating said dispensing mechanism including a plunger movable in said solenoid, an electric system connected with said solenoid normally open, an auxiliary electric system including a magnet and armature, a spring actuated catch engageable 40 with said plunger to hold the same in inactive position, and connections between said catch and armature to release the catch upon the initial movement of the armature.

8. A device of the class described comprising dispensing mechanism, a solenoid mechanism and plunger for actuating said dispensing mechanism, an electric system for said solenoid and terminals therein, normally open, an electromagnetic system including a 45 magnet and armature therefor normally out of contact with said magnet and operatively connected with said terminals to close the same, a switch in said last named system, normally open, a spring controlled catch for the 50 armature, a coin chute and mechanism in proximity thereto operable by the impact of a coin and operatively connected with said switch to close the same, a slide bar capable of the release of said armature catch, a coin 55 pusher supported by said slide bar, a connection between said slide bar and switch adapted to open the same upon the initial 60 movement of the slide bar, a rod in parallel relation with the solenoid plunger connected 65 at one of its ends with a lever operatively

connected with the slide bar, and a lever system connecting said rod with said plunger to move the rod in the same direction as the plunger.

In witness whereof, I have hereunto set 70 my hand this 22d day of February, 1929.

CHARLES F. KURTZ.
